UNITED STATES PATENT OFFICE.

ELMER C. POOL, OF NEW CASTLE, PENNSYLVANIA

PACK-HANDLING APPARATUS.

Application filed August 2, 1921. Serial No. 489,243.

To all whom it may concern:

Be it known that I, ELMER C. POOL, a citizen of the United States, and resident of New Castle, in the county of Lawrence and State of Pennsylvania, have invented certain new and useful Improvements in Pack-Handling Apparatus, of which the following is a specification.

My invention relates to the manipulation of metal sheets and plates, and more particularly to the feeding of such sheets or plates, automatically, one at a time, from a pile to a tinning machine, and has for one of its objects an improved feeding mechanism such as that described in my co-pending application, Serial No. 426,627, filed November 26, 1920, having an improved pack handling mechanism embodied therein, which will so position the pack of plates being fed into the machine that other plates may be added to said pack without interfering with the operation of said feeding mechanism.

Referring to the drawings, Figure 1 is a sectional side elevation of my improved feeding mechanism as applied to a tinning machine, the section being taken on the line I—I of Figure 3.

Figure 2 is a sectional plan taken on the line II—II of Figure 1.

Figure 3 is a sectional rear elevation on line III—III of Figure 1.

Figure 4 is a partial side elevation.

Figure 5 is a perspective view showing details in the construction of the pack handling apparatus forming part of my invention.

In the accompanying drawings, the letter A designates a tinning pot, in itself an old and approved form. The pot is separated transversely by a vertical wall or partition 2, into compartments B and C. The lower edge of this partition or septum 2, which terminates above the bottom of the tinning pot, and the upper edge of a rib or projection 3 on the bottom of the pot defines the width or vertical dimension of a narrow passage or opening D, through which the plates, while submerged in the bath of molten tin, passes from the compartment B into the compartment C of the pot A. The particular pot shown is of a width which permits of two or more plates, side by side, being passed through the tinning pot.

Located immediately above the upper edge of the compartment B, at the plate entering side of the tinning pot, are two sets of feed

rollers E and F, which are arranged to receive the plates from my improved feeding mechanism to be described, and to move them forwardly and downwardly into the 60 tin pot at an angle to the horizontal.

The feed rollers F are at a somewhat lower level than the rollers E, and an adjustable roller G is located on the discharge side of the set F to guide and direct the 65 front end of the successive plates forwardly and downwardly and into the molten tin in compartment B, as they emerge from between the rollers F.

Positioned within the compartment B, 70 closely adjacent to the passage D, is a set of pressure rolls I. These pressure rolls feed the plates from compartment B into the compartment C.

Two sets of feed-out rollers J and K are 75 provided in the compartment C of pot A to feed-out the plates and also to squeeze off surplus tin from the plates.

An inclined apron plate 10 is provided at the entrance end of the compartment B of 80 the pot to receive the plates as they are delivered from my improved feeding mechanism. Other guide plates 12 and 13, are arranged to guide the plates through the rolls F and I, and curved guide plates 14 85 and 14' form a guide N which directs the forward end of the plates emerging from the set of pressure rolls I upwardly into the bite of the lower set J of the feed-out rollers J and K.

My improved feeding mechanism is adapted to be located directly to the rear of the tinning pot and comprises a double set of parts arranged side by side so as to act on two piles of plates at one time, thereby 95 feeding two plates, side by side, into the tinning machine.

A framework or supporting structure 16 is secured to and extends rearwardly from the tinning pot A and supports the several 100 parts comprising my feeding mechanism. A bosh or receptacle 17 is secured to and extends below the framework 16 and is adapted to retain a vertically adjustable plate pile holder. The plate holder comprises a back rest member 19 which is secured to the back wall of the bosh 17 and projects inwardly and downwardly at an angle, so as to slidably support an L-shaped plate retainer 20 which is of sufficient width 110 to hold two piles of plates side by side. The plate retainer 20 is adjustably held in posi-

tion and adapted to be vertically adjusted by means of a pair of chains 21, one of which is secured on each end thereof and passes upwardly over suitable sheaves 22 5 splined on a shaft 23 journaled in the bosh, this shaft having a ratchet and dog operating mechanism 24 on one end outside of the end wall of the bosh.

Mounted on the rear edge of the support 10 framework 16 at each end and center thereof is a bracket 25 supporting a shaft 26, having four arms 27 loosely mounted thereon for pivotal movement.

The arms 27 have a pair of cylindrical 15 magnetic plate lifters Y journaled and supported in their lower ends, and the center arms have their upper ends counterweighted by adjustable counterweights 29 mounted on a projecting arm 30. A locking lever 31 is 20 pivoted on the arms 27, having the counterweights adjacent their upper ends, and such lever is provided with a notch 32 to engage with the projecting tongue 33 on the frame 16 so as to hold the magnetic plate 25 lifters Y out of their plate engaging position when desired.

The magnetic plate lifters Y, each comprises a permanent magnetic member 34 mounted within a pair of hollow cylindrical 30 casings 35, which have their inner ends spaced apart and joined by a non-magnetic hollow cylindrical tubular member 36. Stub shafts 37 are threaded into the outer ends of the casings 35 and support the whole 35 structure in suitable bearings formed in the lower ends of the arms 27.

The hollow cylindrical casing members 35 are formed from soft iron or other material which will readily convey the circuit or 40 attracting forces from the permanent magnet 34, thus forming unlike poles through which a circuit will be completed when they contact with a plate.

The outer surface or periphery of the 45 members 35 is fluted, forming a series of knife edge ribs or projections 39. It will thus be seen that each of the ribs or projections 39 will successively engage a plate as the magnet is rotated, and that projections 50 on the opposite casings will form opposite or unlike pole contacts, and that such projections will contact with the face of the outermost plate of the pile in the retainer 20. The effect of the knife edge contacts will be 55 to concentrate the forces of the magnet in the immediate plate and prevent the spreading of the forces through and into the next adjoining plates.

Suitable cross-beams 40-40' are arranged 60 to extend from one end of the frame support 16 to the other immediately above the upper edge of the bosh, and carry suitable curved guide strips 41-42 arranged to form an upwardly and inwardly inclined passage 65 way to guide the plates being conveyed.

A second pair of cross-beams 43-43' is arranged forward and above the cross-beams 40, and carry other guide strips 44-45 forming a second passage-way adapted to receive the plates from the passage-way between the strips 41-42, and direct them forwardly and upwardly between suitable pinch rollers 46 and 47 of any well-known construction.

The lower one of the pair of pinch 75 rollers E is driven by a suitable source of power and carries a sprocket 48 on each end. The pinch roller 46 also carries a sprocket 48^a on each end in line with the sprocket 48, and a third sprocket 48^b is mounted on each 80 end of the shaft 26 in line with the sprockets 48 and 48^a. A link chain 49 is trained about the sprockets 48, 48^a, 48^b, thus driving the pinch rollers E, pinch rollers 46 and 47, and shaft 26 at the same speed. It will be understood that if found desirable in practice, a single set of drive sprockets may be used.

A pair of sprockets 50 of somewhat smaller diameter than the sprockets 48, 48^a, 48^b are mounted on the ends of the shaft 26, 90 and a sprocket 51, of greater diameter than sprockets 50, is mounted on the end of the outside stub shafts 37 of each magnetic conveyer. A link chain 52 is trained over the sprockets 50 and 51 to constantly drive the 95 conveyer members, which will necessarily revolve at a lesser speed than that of the pinch rollers E and pinch rollers 46, 47, due to the difference in size of the sprockets 50 and 51.

A cross-beam member 54 is arranged forward of the rollers 46-47 and has two pairs of suitable spaced depending lugs 55 which support pivot shafts 56 adapted to have guide plates 57 hingedly supported thereon. 105 Plates 57 have a crank arm 58 secured thereto which abuts the cross-beam 54 when the plate is in its lowermost position, and carries a counterweighted lever 59 to normally hold it in such position.

Supported on suitable cross-beams 60 forward of the hinged plates 57, and in proximity thereto, is a pair of guide plates 61. The plates 61 are composed of top and bottom pointed portions, the top portion being directed forwardly over the rollers E and the bottom portion directed downwardly and forwardly to the passage between the rollers E.

The inclined apron 10 of the tinning pot 120 is arranged below the plates 57 and 61, and completes the passage-way to the rollers E.

The hinged counterweighted guide plates 57 serve as a trap so that if more than one plate or sheet should be carried through the pinch rollers 46-47 they will bear against the guide plate 57 with sufficient force to counteract the effect of the counterweighted lever 59 and raise the guide plate, thereby allowing the plurality of feed plates or 125 130

sheets to pass over the dual guide plates 61 and away from the tinning pot.

Magnetic separators X are mounted above each of the magnetic plate lifters Y and comprise a rectangular casing member 63 pivotally supported on the cross-beam 40. The casings 63 contain a permanent magnet 64 and are provided with blade or knife edge poles 65 which extend into the path of the lifted plates and contacts with the rear faces thereof. The magnet 64 is of less strength than the magnets of the plate lifter Y, and therefore, will not materially retard the movement of the plates, yet it is of sufficient strength that if two plates should stick or in some manner be lifted together, it will retard the movement of the second plate, and thus separate them.

A still further means for preventing the feeding of more than a single plate into the tinning pot is located just to the rear of the pinch rollers 46-47, and comprises a shaft 67 journaled in the frame support 16 and having a plurality of locking fingers 68 secured thereon of triangular shape, and of such size that their flat sides will extend past the guide strips and into the path of the lifted plates. As the plates are guided between the strips 44 and 45, they will bear against the upper strips 45 due to the direction of their travel, and in this position they will strike the fingers 68 and cause the shaft and fingers to rotate one-third of a revolution, thereby presenting one of the other faces of the fingers against the plate. If a second plate is overlapped on the first in such a manner that its forward edge is disposed to the rear of the forward edge of the first plate, it will strike the fingers and be held, since the fingers cannot again rotate until the first plate has passed clear from under the fingers.

Another feature and function of these fingers is that they will cause an even feed of the plates from both of the magnetic feed rollers Y, since if one roller feeds a plate in advance of the other, the first to reach or strike the fingers 68 will rotate them the one-third turn, and then lock them against rotation until it has passed from thereunder, and the plate that is in the rear will be held until the fingers are again freed when another plate will be presented by the other magnetic feed roller to follow the one just clearing the fingers, thus causing the newly presented plate, and the held plate to pass together into the bite of the rollers 46-47.

As the plate lifters Y are rotated to feed the plates from the pile or pack, it becomes necessary to renew the pack from time to time and in order to do so without interfering with the operation of the machine, I have provided a pack shifting or handling mechanism which comprises a pair of U-

shaped yoke members 70. The yoke members have their side arms pivotally mounted as at 71 to the lower ends of levers 72, which have their upper ends keyed or otherwise secured to operating shafts 73. The shafts 73 have their outer ends journaled in rack plates 74 and their inner ends journaled in a single double bracket 75 which is secured to the forward wall of the bosh 17 by bolts 76 or the like.

Each of the operating shafts 73 extends beyond the rack plates 74 which are bolted to and extend upwardly from the end walls of the bosh 17.

A suitable operating lever 78, secured to the outer end of each of the shafts 73, is provided with a hand grip 79 for the operator to grasp.

The side arms of the U-shaped yoke members 70 normally rest upon and ride across the shoulders or bearing bosses 27^a on the lower ends of the arms 27, in which the stub shafts 37 of plate lifters Y are journaled.

It will be readily apparent that when the operator grasps the lever 78 and rocks it in a forward direction it will so rotate the shaft as to move the yoke 70 rearwardly. As the yoke is moved rearwardly the operator will either grasp the yoke itself and manually lift it upwardly to clear the pack of plates being fed into the machine and then let it drop behind said pack, or he will grasp the flexible cable or chain 77 which has one end secured to the one side bar of the yoke and its other end secured to the shaft 26, and thus lift the yoke.

In order to hold the yoke in various adjustable positions, a spring pressed pawl 80 having operating handle or grip 81 is mounted on the lever 78 and is adapted to be engaged in the upper serrated or toothed edge 81' of the rack plate 74.

When the operator desires to renew the pack of plates he will move the yoke for that pack rearwardly and lift it over the pack as described above. He will then move or rock the lever 78 rearwardly so as to move the yoke forwardly, which will pull the remaining plates of the pack with it, and when the pack has been moved forward to the desired position, he will release the pawl 80 and lock the yoke in position. He may then renew the pack by adding plates to the rear of the original pack. When sufficient plates have thus been added, the yoke will be moved rearwardly and disengaged from the original pack.

A forward rest 82 is secured to the forward wall of the bosh 17 to prevent the plates being tilted forward beyond a point where they may be operatively engaged by the plate lifters Y.

The operation of my improved feeding mechanism will be readily understood from

the above description taken with the accompanying drawings. The peculiar and novel construction of magnetic plate lift will cause the magnetic forces to be concentrated 5 on a single plate of the pile and will lift it through the guide passages to the pinch rollers 46—47, which will in turn feed it to the pinch rollers E of the tinning pot.

The operations of the three separate 10 mechanisms for preventing more than one plate being carried to the tinning pot, have also been fully described above, and will not be gone into again, although these mechanisms are important features and are distinct improvements over any devices heretofore known.

It will be readily understood that while I have described my invention in combination 15 with a tinning pot, it is not limited to such use, but may be used, wherever desired, to feed single plates, and therefore I do not wish to be limited to such a combination.

It will also be understood that while I have shown and described one embodiment 20 of my invention with great particularity, I do not wish nor do I intend to limit my invention to such structure, since various modifications in structure and combination 25 of parts may be made without departing from the spirit of my invention as defined in the appended claims. For instance, wound active magnets may be substituted for the permanent magnets shown, or other such substitutions of equivalents made as 30 found necessary or desirable.

I claim:—

1. In an automatic plate feeding mechanism, a substantially L-shaped plate holder 35 for supporting a pack of plates, said holder being inclined rearwardly to support said plates in an inclined position, means for feeding plates from said pack, and means for moving said plates away from the back of said holder, so as to permit the insertion 40 of other plates between said pack and said supporting means.

2. In an automatic plate feeding mechanism, means for supporting a pack of plates,

means for feeding plates from said pack, and means for moving said plates from said supporting means so as to permit the insertion 50 of other plates between said pack and said supporting means, said means including a U-shaped yoke member adapted to be engaged around said pack, and means for 55 moving said yoke and said pack forwardly away from said supporting means.

3. In an automatic plate feeding mechanism, a substantially L-shaped plate holder for supporting a pack of plates, said holder 60 being inclined rearwardly to support said plates in an inclined position, means for feeding plates from said pack, and means for moving said plates away from the back of said holder, so as to permit the insertion 65 of other plates between said pack and said supporting means, said means including an operating shaft, levers on said shaft, a U-shaped yoke member pivotally mounted on said levers adapted to be engaged around 70 said pack and to move said pack forwardly away from the back of said plate holder when said shaft is rocked, and means for rocking said shaft.

4. In an automatic plate feeding mechanism, a substantially L-shaped plate holder for supporting a pack of plates, said holder 75 being inclined rearwardly to support said plates in an inclined position, means for feeding plates from said pack, and means 80 for moving said plates away from the back of said holder, so as to permit the insertion of other plates between said pack and said supporting means, said means including an operating shaft, levers on said shaft, a U- 85 shaped yoke member pivotally mounted on said levers adapted to be engaged around said pack and to move said pack forwardly away from the back of said plate holder when said shaft is rocked, a lever for rocking said shaft, and a pawl and rack adapted to co-operate to lock said shaft and yoke in 90 its various positions.

In testimony whereof I have hereunto signed my name.

ELMER C. POOL.
